UNITED STATES PATENT OFFICE.

HARRY C. GAMAGE, OF NEW YORK, N. Y., ASSIGNOR, BY MESNE ASSIGNMENTS, TO OIL-BATH LUBRICATOR CO., A CORPORATION OF NEW JERSEY.

DEVICE FOR SECURING SPINDLES TO SHAFTS.

No. 864,779.

Specification of Letters Patent.

Patented Sept. 3, 1907.

Application filed May 17, 1907. Serial No. 374,239.

To all whom it may concern:

Be it known that I, HARRY C. GAMAGE, a citizen of the United States, residing at New York, in the county of New York and State of New York, have invented a certain new and useful Improvement in Devices for Securing Spindles to Shafts, of which the following is a specification.

The invention is a device for attaching a spindle to an axle or shaft, so that it will be coaxial therewith and firmly secured thereto. A spindle thus affixed may be used, for example, in connection with car axles for actuating axle lubricating mechanism, or speed recording mechanism, and in connection with shafts in general for transmitting motion to gearing which it may not be desirable to drive directly from the shaft itself.

In the accompanying drawings—Figure 1 is an end view of a car axle showing my device in place. Fig. 2 is a section on the line *xx* of Fig. 1, showing the device with the knife edge flanges on the resilient bar bearing on the face of the axle, and Fig. 3 is a similar view showing the disk flange seated on the end face of the axle and said knife edges entering the metal of said face.

Similar numbers of reference indicate like parts.

1 is the end of a car axle having the usual centering opening 2. On the interior of this opening 2, I form a screw thread of any suitable means. This can readily be done while the axle is in place under the car and without removing said axle, by any convenient hand tapping device.

30 The spindle has a cylindrical outer portion 3 and an inner threaded portion 4. Integral with said spindle is a disk 5, having a polygonal shouldered projection 6 to receive a wrench. At its outer periphery said disk has a flange 7. On the spindle and adjacent to the disk 5 is a locking bar 8 of spring metal, the ends of which are preferably bent toward the axle face and extend through the recesses in the disk flange 7. On each side of each end of bar 8 are formed knife edge flanges 9. The bar 8 is rigidly secured on the spindle by any suitable means, as by raising a chip of the metal of the spindle and riveting or crowding the same upon said bar as indicated at 10, Figs. 2 and 3.

In securing the device in place, the threaded end 4 of

the spindle is inserted in the threaded opening 2 and the spindle is turned by a wrench applied to projection 45 6, until the disk flange 7 bears upon the end face of the axle. As the knife edges 9 meet said face before the flange meets it (see Fig. 2), it is obvious that when said flange finally seats itself on said face, the spring bar 8 will have yielded and by its resiliency will be pressing 50 55 the knife edges 9 against said face. The knife edges are to be tempered hard, so that a few blows of a hand hammer delivered upon the bar 8 will drive them into the metal of the axle face, as shown in Fig. 3, thus locking the spindle and preventing its rotation.

The special advantage of this device is the ease with which it can be applied to any shaft or axle already having a central centering opening in the end, since all that is necessary is to tap the thread on the interior of the opening. No special holes are cut and there is no 60 need for disspacing shaft or axle from its usual or working position.

I claim:

1. The combination of a spindle having a threaded end, and, fast on said spindle, a flanged disk and a resilient bar having a knife edge flange, the said bar extending through an opening in the flange of said disk. 65
2. The combination of a spindle having a threaded end, and, fast on said spindle, a flanged disk and a resilient bar extending through an opening in the flange of said 70 disk and having at its end a knife edge flange.
3. The combination of a spindle having a threaded end, a flanged disk formed integrally with said spindle, and a resilient bar, rigidly secured on said spindle and in proximity to said disk, extending through openings in the 75 flange of said disk and having, at its ends, knife edge flanges.
4. The combination of a shaft having a central threaded recess in its end face, a spindle having a threaded end constructed to be received in said recess, a flanged disk on 80 said spindle, a resilient bar on said spindle having its ends extending through openings in the flange of said disk and knife edge flanges on the ends of said bar constructed to meet and be held against the said end face when said spindle is in place in said recess. 85

In testimony whereof I have affixed my signature in presence of two witnesses.

HARRY C. GAMAGE.
